WILLIAM HOOPES AND THEODORE VARNEY, OF PITTSBURGH, PENNSYLVANIA.

TROLLEY-CONDUCTOR.

1,157,394.

Specification of Letters Patent.

Patented Oct. 19, 1915.

Original application filed July 17, 1914; Serial No. 851,462. Divided and this application filed September 1, 1915. Serial No. 48,406.

To all whom it may concern:

Be it known that we, WILLIAM HOOPES and THEODORE VARNEY, citizens of the United States, and residents of Pittsburgh, in the county of Allegheny and State of Pennsylvania, have invented a new and useful Improvement in Trolley-Conductors, of which the following is a specification, this application being a division of our application Serial No. 851,462, filed July 17, 1914.

Our invention relates to overhead electric railway structures and particularly to structures of the so-called catenary type.

The object of our invention is to provide a conductor of relatively light weight that shall have a large current-carrying capacity and such strength and rigidity as to adapt it to withstand the heavy pressure and shocks of current-collecting devices that are employed upon such railway locomotives and cars as are operated at high speeds and that shall automatically compensate for expansion and contraction, under changes in temperature, without danger of buckling or being subjected to undue strains, at any season of the year or under any operating conditions.

In the operation of railways by electricity, the tendency is toward the use of high voltages and large amounts of power. Heretofore, when high voltages have been employed, conductor wires of comparatively small cross-section, similar to those which have been used on so-called trolley roads, have been suspended over the track by means of supporting structure of the catenary or other type. On account of the high voltage and on account of the trouble due to ordinary trolley wheels leaving the wire at high speeds, it has generally been necessary to use some form of sliding shoe or roller collector. Furthermore, on account of the necessity of having the wire sufficiently high above the rail to clear ordinary freight cars having men on them, and also because there are usually low bridges or other obstructions which require the wire to be lowered at certain points, the framework which supports the collecting shoe has necessarily been of

such substantial construction that very considerable pressure has been necessary to keep the collector in contact with the wire. It has also been found that the various forms of small wire conductors suspended over the tracks and kept taut under a relatively high longitudinal stress have caused difficulty, on account of changes of temperature. Devices, embodying springs, have been tried for maintaining a comparatively uniform tension on the conductor wire but, on account of the high tension such devices have been very heavy, cumbersome, and, in the main, unsatisfactory.

The most successful type of stationary conductor which has been used, in so far as the collection of current therefrom by a moving train is concerned, has been the third rail. The reason for this has been that the rail is rigid and has a relatively large amount of transverse stiffness so that relatively heavy pressure may be employed in the collecting shoe without producing distortion in the contact. When, however, it is necessary to use high voltages, as well as to meet certain other conditions of service, it is advisable to have the conductor overhead rather than beside the track. Our present invention is designed to combine, in an overhead conductor suitable for use with high voltages, the mechanical running qualities of the third rail. For this purpose we have devised the arrangement shown in the accompanying drawings, in which—

Figure 1 is a diagrammatic side elevational view of a portion of an overhead structure embodying our invention, parts being broken away. Fig. 2 is a view, in side elevation, of the adjacent ends of two conductor sections and their connecting devices, and Fig. 3 is a sectional view taken on line A—A of Fig. 2.

We employ a continuous strip 1 of metal of preferably, though not necessarily, rectangular cross section having high electrical conductivity, the thickness of which is small, as compared with its width. For example, a strip of aluminum one-fourth inch thick by two inches wide is suitable for the pur-

pose. The strips 1 may be produced, for convenience in handling, in lengths of three hundred feet or thereabouts. They may be rolled up for shipment and be unrolled and installed at the place of use. Although any one of a variety of means for supporting the strips may be employed, a suitable means comprises a steel catenary cable, 2, supporting structures 3, that may be spaced approximately three hundred feet apart, and hangers 4 that may be suitably connected to the conducting strip and to the cable at intervals of approximately ten feet.

In order that the conducting strips 1 may not be worn away or otherwise injured by the collector, we provide shoes 5 at the lower edge of the strip, which may be of comparatively cheap material and not necessarily of high electrical conductivity, since they are in immediate contact with the conducting strip. For example, a suitable material for the shoes is galvanized steel. The shoes may be of any desired and suitable length and cross sectional form and may be attached to the strip 1 by any suitable means.

On account of the longitudinal expansion and contraction of the conductor strips 1, under changes in temperature, springs 6 may be inserted between the adjacent ends. The springs 6 may have a maximum movement of approximately six inches and may give a maximum tension, when extended, of about five hundred pounds, and a minimum tension, when closed, of about two hundred pounds. The object of this tension is to facilitate the expansion and contraction of the strip without causing buckling, but it will be observed that the tension is so low that the results indicated may be obtained by a comparatively light spring, which will be cheap and will not occupy much space. Springs of any type or kind having suitable strength and resilience may be employed but, as desirable examples, we have shown in the drawings, springs of the leaf type that are disposed at right angles to the strips 1, to the ends of which they are attached by means of members 7. As shown, the members 7 are riveted to the lower ends of the spring members and are pivotally fastened to the ends of the strips. Any suitable auxiliary bonding means 11 for the adjacent ends of the conductor strips may, of course, be employed.

For the purpose of guiding the collector smoothly over the joint between the ends of the strips, we provide side plates 8 the lower edges of which deviate upwardly, in a slight degree, from a straight line toward their ends and terminate in rounded corners. The side plates are clamped in position by bolts 9 or otherwise, and, at one side of the joint between the meeting ends of the strips

1, they are provided with longitudinal slots 10 to receive the bolts 9 in order that expansion and contraction of the strips 1, under changes in temperature, may not be prevented.

The contact shoes may, of course, be made of the same lengths as the conductor strips 70 or of any other length that may be desired. If relatively long shoes are employed, it will probably be found necessary or advisable to employ springs between their adjacent ends, that may be similar to those employed between the ends of the conductor strips, as indicated in Figs. 2 and 3 of the drawings.

The structural details of our invention may obviously be otherwise variously modified from what we have specifically shown and described, within the scope of the appended claims.

We claim as our invention:

1. A trolley conductor comprising long strips of good-conducting material supported end-to-end, resilient members connecting adjacent ends of said strips, and a plurality of contact pieces disposed along the said strips. 90

2. A trolley conductor comprising a plurality of long strips of metal disposed end-to-end, springs for connecting the ends of said strips together, bridging strips for the joints between said ends, and contact pieces disposed end-to-end along the said long strips. 95

3. A trolley conductor for electric railways, comprising long end-to-end strips of aluminum, springs interposed between the ends of said strips, bridging strips for spanning the joints between said ends, contact pieces disposed end-to-end and slightly spaced apart, and means for clamping said contact pieces against the bottom edges of said aluminum strips. 105

4. A trolley conductor comprising long strips of good-conducting material disposed end-to-end, hanger rods disposed at intervals along said strips, resiliently expansible hangers for the adjacent ends of said strips, and contact pieces disposed along the said strips. 110

5. A trolley conductor comprising a plurality of long strips of metal disposed end-to-end, resiliently expansible hangers for the adjacent ends of said strips, bridging strips for the joints between said ends, and contact pieces disposed end-to-end along the said long strips. 120

6. A trolley conductor for electric railways, comprising long end-to-end strips of aluminum, resiliently expansible hangers for the adjacent ends of said strips, bridging strips for spanning the joints between said ends, contact pieces disposed end-to-end 125

and slightly spaced apart, and means for clamping said contact pieces against the bottom edges of said aluminum strips.

7. A trolley conductor comprising long strips of good-conducting material disposed end-to-end, hanger rods disposed at intervals along said strips, double leaf-spring hangers for the ends of said strips, and contact pieces disposed along the said strips.

Copies of this patent may be obtained for five cents each, by addressing the "Commissioner of Patents, Washington, D. C."

In testimony whereof, we have hereunto 10
subscribed our names this 12th day of Au-
gust, 1915.

WILLIAM HOOPES.
THEODORE VARNEY.
